UNITED STATES PATENT OFFICE.

HARRY GOULD, OF KINGSTON, PENNSYLVANIA.

ATTACHMENT FOR ARTIFICIAL LIMBS.

1,368,136.

Specification of Letters Patent.

Patented Feb. 8, 1921.

Application filed November 8, 1920. Serial No. 422,552.

To all whom it may concern:

Be it known that I, HARRY GOULD, a citizen of the United States, residing at Kingston, in the county of Luzerne and State of Pennsylvania, have invented new and useful Improvements in Attachments for Artificial Limbs, of which the following is a specification.

This invention relates to improvements in artificial legs, the principal object of the invention being to provide improved means for connecting the "chord" which connects the foot part with the shank, to the said foot part and shank.

Another object of the invention is to provide a bearing plate for connection with the foot part to which the chord and the ankle bolt are connected.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:—

Figure 1 is a view partly in section showing my improved artificial leg.

Fig. 2 is a bottom plan view of the foot part of the leg.

Fig. 3 is a perspective view of the plate.

Fig. 4 is a view of a modified form of the plate.

Fig. 5 is a sectional view on line 5—5 of Fig. 1.

In these views 1 indicates the foot part of the leg and 2 the shank part. These parts are connected together by the flexible chord 3, the elastic strap 3' and the ankle bolt 4 which is provided with the pivotal joint 5. These parts are constructed as usual and will not be described in detail. The upper ends of the chord 3 and strap 3' are held to part 2 by means of a wooden pin 6 which passes through eyes in the upper ends of said parts and has its ends seated in bushings 7 located in holes in the walls of part 2.

The under face of the heel part of foot 1 is recessed to receive plate 8 which is provided with the opening 9 and the strip on each side of said opening being bent upwardly to form the loop 10. The lower end of chord 3 fits between these loops and the

beam or pin 11, formed of hard wood, is passed through the eye in this end of the chord 3 and has its ends engaging the loops. The plate is provided with an extension 12 which is connected with the main part of the plate by the right angular portion 14. This part 12 is provided with a hole 15 to receive the threaded end of the ankle bolt 4 and acts as a washer for the nut 16 on said bolt. The rear end of the plate is provided with an upwardly extending tongue 17 which engages the heel of the foot part and acts to stabilize the parts.

On the old style of legs the parts 12 and 14 can be omitted from the plate, as shown in Fig. 4, as in this case the washer is not needed.

From the above it will be seen that chord 3 can easily be removed and replaced by a new one by knocking out the pins 6 and 11. The plate which forms the bearing for pin 11 will prevent the crushing of the wood, from which the foot part 1 is formed, by said pin as is the case in wooden legs now on the market.

Where a metal foot is used the plate is not necessary and the pin 11 only is used.

It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:—

1. An artificial leg comprising a foot and a leg part pivotally connected together, a plate in the heel portion of the foot part, a pin, means for removably holding the pin on the plate and a chord connected with the leg part and having its lower end engaged by the pin. 95

2. An artificial leg comprising a leg part and a foot part pivotally connected together, a plate in the heel portion having a slot therein, loops on the plate, one on each side of the slot, a chord connected with the leg part and having its end located between the loops and a pin engaging the loops and passing through the eye in said chord. 100

3. An artificial leg comprising a leg part and a foot part pivotally connected together, a plate in the heel portion having a slot therein, loops on the plate, one on each side of the slot, a chord connected with the leg part and having its lower end located between the 110

loops, a pin engaging the loops and passing through the eye in said chord and an upwardly extending tongue on the rear part of said plate engaging the rear of the heel 5 part of the foot.

4. In combination with the leg and foot parts of an artificial leg, a chord connecting said parts together, an ankle bolt also connecting the parts together, a plate in the 10 lower face of the foot part having upwardly

extending loops thereon spaced apart, said chord having a perforated lower end located between the loops, a pin engaging said loops and passing through the perforation and an extension on the plate having an opening 15 therein for receiving the end of the ankle bolt and acting as a washer therefor.

In testimony whereof I affix my signature.

HARRY GOULD.
